UNITED STATES PATENT OFFICE.

DANIEL W. BOWMAN, OF TOLEDO, OHIO.

STOVE FOR HEATING PURPOSES.

SPECIFICATION forming part of Letters Patent No. 687,671, dated November 26, 1901.

Application filed March 11, 1899. Renewed October 10, 1901. Serial No. 78,255. (No model.)

To all whom it may concern:

Be it known that I, DANIEL W. BOWMAN, a citizen of the United States of America, and a resident of Toledo, in the county of Lucas 5 and State of Ohio, have invented certain new and useful Improvements in Stoves for Heating Purposes, of which the following is a specification.

My invention relates to improvements in 10 stoves such as are used for heating purposes and, further, such as are used for burning all kinds of gas, vapor, and oil fuels; and the objects of my invention are, first, to economize the consumption of such fuels and obtain 15 a much larger percentage of heat, and, second, to adapt one single stove to the use of a burner for the consumption and use of these various kinds of fuel. I attain these objects by the mechanism illustrated in the 20 accompanying drawings, in which—

Figure 1 is a front elevation of my invention complete. Fig. 2 is a vertical center section view of the same.

Similar letters refer to similar parts throughout both views.

The burners and the piping and lighting system shown here are the subject-matter of a separate application, filed March 2, 1899, Serial No. 707,485, and are used here only in 30 combination and in a general way to show the features of the stove as adapted to its use and advantages.

Referring to the drawings, A is the base, supported on feet *a a a*, and the upper side of 35 it is provided with a groove or offset inside of which the shell B of the lower damper or burner-chamber sets. This shell B is provided with two or more damper-doors *b b* and capped by a damper-ring I above, which 40 forms the base of the upper burner-chamber, which consists of the shell C and its doors *c c* and mica *c' c'*. A diaphragm H separates these upper and lower burner-chambers and forms a support for the burners to rest on 45 and also forms a wall through which to admit the air from the outside into the upper burner-chambers by the outside damper-ring J, with its openings and handles *j j*, by which it may be partially rotated to open and close 50 it, as desired.

A burner D is arranged in the stove to show its location in the stove and the adaptation of

the stove to the use of the burners and also the system of valves *d* and *d* and pipes *d' d'*, and *d''*, which shows the feed to the burner 55 D and the manner of taking off the gas for the light, as indicated.

The burner-chambers are capped with a double-flanged ring K, which completes the stove up to the corrugated heating-drum E 60 or upper section of the stove, and all of these lower parts and section described are secured together in the usual substantial manner with bolts and screws. The ring K is provided with a recess on its top side to receive 65 the base of the corrugated heating-drum E, which projects below its base-ring L, and the two upper and lower sections are hinged together at this point by the hinge M on the back of the stove and the catch N on the front, 70 locking over the lug *n* on the ring K, which hinge and joint admits of free access to the interior of the stove above the burner, while at the same time when this upper section is turned back a gravity-support P, that is 75 hinged at *P'* on the back of the stove, drops down and forms a support for it. The rising hot air is retained by and the heat radiated from the heating-drum E, and when it reaches the top of the drum E it may pass out through 80 the register or top damper S in the top plate R, which register or damper is operated by the knobs *S' S'* being slightly rotated. The ornamental cover T is provided with venti- 85 lating-holes, which allow the hot air to pass out into the room when the top damper is open. The ornamental cover T may be lifted off at any time to set anything on the stove. If desired at any time, the stopple O may be removed and the pipe attached. 90

Having clearly described and illustrated my invention, it may be clearly and easily seen that I have provided for air circulation and easy access to all parts of the burner and control the inlet and outlet of air to the heating-drum, so as to obtain and throw off the greater amount of heat from the burners and from the drum, and by means of a branch pipe *d' I* provide a way to take off purified and enriched gas for lighting purposes. 95

What I claim as new, and desire to secure by Letters Patent, is—

In a heating-stove for gas and oil burners the combination of a lower exterior shell pro-

vided with dampers and doors and forming a double burner-chamber the lower chamber B, as an air-chamber and the upper chamber C, as a fire-chamber the two chambers separated by a diaphragm-plate H, which supports the burner D, and is also provided with an exterior damper-controlled passage for cold air into the fire-chamber C, together

with the burner D, with its inlet and outlet pipe, substantially as shown and described. 10

Signed by me at St. Louis, in the State of Missouri, this 9th day of March, 1899.

DANIEL W. BOWMAN.
